CLAIM

The ornamental design for an earphone and charging case set, as shown and described.

DESCRIPTION

FIG. 1 is a perspective view of an earphone of the earphone and charging case set, shown separately for ease of illustration;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a charging case of the earphone and charging case set, shown separately for ease of illustration and in a closed configuration;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a perspective view of the charging case of the earphone and charging case set, shown separately for ease of illustration and in an open configuration; and,

FIG. 16 is a perspective view of the earphone and charging case set, shown in use with the earphone received in the charging case.

The broken lines and the areas of lower opacity within the broken lines form no part of the claimed design.

1 Claim, 16 Drawing Sheets
